UNITED STATES PATENT OFFICE.

SAMUEL MARKHAM BRYDGES, OF LONDON, ENGLAND.

PORTABLE CIGARETTE-MAKING MACHINE.

Application filed February 25, 1925, Serial No. 11,403, and in Great Britain February 28, 1924.

This invention relates to a small and compact cigarette-making machine such as may be carried conveniently in the pocket, or constructed in more substantial manner and combined with a stand or the like for table, shop or analogous uses. The said machine is of extremely simple form, and by means especially of the tucking device to be described, is very effective in operation, serving speedily to make a neat cigarette.

In its essentials, there is employed a body member formed with a substantially semi-cylindrical trough across which a paper can be laid and pressed into the trough with its side edges projecting. The trough with the paper therein is then filled with tobacco, one side of the paper lying across the top of the tobacco. A curved former plate, attached to the body, is now turned over so as to lie upon the paper over the trough, and a tucking member, such as an arcuate plate, is movably attached to the former plate so that it can be moved down one side of the trough relatively to the curved former plate, wrapping the one edge of the paper around the tobacco, and so completing the rolling of the cigarette.

Another trough or recess is formed in the body parallel and adjacent to the main trough aforesaid, so that a packet or wad of cigarette papers can be gripped therein by its edge, and one separated therefrom and laid across the main trough as and when required. The wrapping action of the tucking member also serves to detach the paper from the wad, pulling the edge out of the paper trough.

Other features of construction, and subsidiary details will be apparent as the description develops, and, in order that the said invention may be clearly understood, drawings are appended, in which:—

Figure 1 is a side view of one form of machine according to the invention, opened out ready for use.

Figure 2 is a plan view thereof.

Figure 3 is a transverse sectional elevation taken on the line III—III, Figure 2.

Figure 4 is a partly sectional view similar to Figure 3, with the parts in the closed position as when making a cigarette.

Figure 5 is a perspective view of the device according to Figures 1-4, with the parts totally closed for the pocket.

Figure 6 is a perspective view of a lighter

or cheaper form constructed from bent or stamped metal.

Figure 7 shows, in transverse section, a modification hereinafter described.

Referring firstly to the construction shown in Figures 1-5, 1 denotes a body which may be of cast metal. This is formed with a main semi-cylindrical trough 2 extending from side to side, and lying adjacent and parallel to a paper containing trough 3. The latter is adapted to receive the edge of a wad or packet of papers 4 which are or may be retained therein by a slideable pin 5 carried by a spring plunger 6 normally keeping the pin pressed up across the trough 3 into a niche or hole on the other side. Or any other paper gripping means may be substituted.

On top of the body 1 is a platform 7 to which is hinged a flap 8 terminating in a curved former plate 9. The arrangement is such that when a paper has been laid across the trough as in Figure 3 (see 4*), and tobacco filled into the trough on top of the paper, the flap 8 can be swung over, and the former-plate 9 brought on to the top of the protruding paper which has been folded over the tobacco. A curved tucking plate 10, mounted in slide lugs 11 on the former 9, is now moved round down into the trough—see Figure 4—to tuck in the paper edge. The flap 8 is then lifted, the paper edge damped and the cigarette removed. A cavity 12 may be formed in the body 1 to accommodate a brush 13 kept moistened by a packing of damp wadding or the like, so that the paper may be moistened when the cigarette is made.

The tucker 10 is formed with a projecting flange to facilitate operating, and the platform 7 is preferably mounted on the body 1 with a degree of sliding movement by means of slots and pins 14, in order that, when not in use, the plate 8 can be folded over with the former-plate lying in the paper trough (see Figure 5), the wad 4 being neatly folded between platform 7 and plate 8.

Referring to Figure 6, the body is made from a sheet of metal formed with a trough 15 for the edge of the paper wad, the trough being sprung open to grip same. The main or cigarette trough 16 is formed with the curled top part 17 constituting the former-plate, and the tucking member 18 is mounted in the lugs 19 similarly to the first described

construction. The operation of cigarette-making is similar to that with the Figures 1-5 form.

Turning to Figure 7, it will be seen that 5 the solid form of Figures 1-5 has been retained, but the mounting of the former 9 is somewhat changed, in that the former plate 20 is hinged at 22 near the edge of the cigarette trough 21. The tucker-plate 23 is 10 carried on the former as before. An alternative construction of pin 24 is shown, this being part of a spring member 25 capable of being sprung over the edge of the paper trough 26 as shown. When not in use the 15 whole is enclosed by a flexible wrapping member 27 which is fastened on to the loop of the spring member 25.

It has previously been proposed to construct a pocket cigarette-making device in 20 the form of a body having a cylindrical trough to receive tobacco on top of a paper laid therein with its side edges projecting, a separate curved former member being provided to co-operate with said trough and a 25 lip on the curved former member serving to wrap one paper edge around the tobacco in the trough.

What I claim as my invention and desire to secure by Letters Patent is:—

1. Pocket cigarette-making machines comprising a body formed with a semi-cylindrical trough to receive tobacco on top of a paper laid therein with its side edges projecting, a curved former plate connected to the body and arranged to lie over said trough, and a tucking member attached to the former plate in such a way that it can be moved relatively to such plate to wrap one paper edge around the tobacco in the trough substantially as described.

2. Pocket cigarette-making machines comprising a body formed with a recess to accommodate a wad of papers by their edge, a trough adjacent and parallel thereto to receive tobacco on top of a paper laid therein from the attached wad, a curved former connected to the body and arranged to lie over said trough, and a curved tucking member slidably mounted on the former so as to tuck the projecting paper edge into the trough, substantially as described.

Dated the 9th day of February, 1925.

SAMUEL MARKHAM BRYDGES.
